(57) **CLAIM**

The ornamental design for a wheel, as shown and described.

DESCRIPTION

FIG. 1 is a perspective view of a wheel, showing my new design; and,

FIG. 2 is a front view thereof.

The broken line showing of the rear portion of the wheel is included for the purpose of illustrating environment and forms no part of the claimed design.

1 Claim, 2 Drawing Sheets**FIG. 1**

FIG. 2
